UNITED STATES PATENT OFFICE.

HENRY A. SMEDBERG, OF NEW YORK, N. Y., ASSIGNOR TO UNION TYPEWRITER COMPANY, OF JERSEY CITY, NEW JERSEY, A CORPORATION OF NEW YORK.

TYPE-WRITING MACHINE.

No. 872,543.

Specification of Letters Patent.

Patented Dec. 3, 1907.

Application filed February 6, 1906, Serial No. 299,805.

To all whom it may concern:

Be it known that I, HENRY A. SMEDBERG, citizen of the United States, and resident of the borough of Manhattan, city of New York, in 5 the county of New York and State of New York, have invented certain new and useful Improvements in Type-Writing Machines, of which the following is a specification.

My invention relates more particularly to 10 type actions of the character embodied in the Monarch typewriter, and has for its principal object to provide a bell-crank-and-fulcrum-bar construction wherein the friction of the contacting parts is reduced to a minimum and the construction thus rendered more durable, as well as easier of action.

In the accompanying drawings, Figure 1 is a vertical sectional elevation of a Monarch style of type bar action embodying my invention, the view being taken substantially centrally and longitudinally of the machine. Fig. 2 is a like view of a modified construction.

Referring particularly to Fig. 1, the key lever is marked 2, and, as in the Monarch 25 machine, is normally held up against its fulcrum plate 3 and against a front pad 4 by a lifting spring 5, secured at its rear end to the fulcrum plate or some other fixed part of the machine, and connected at its forward, free 30 end to a loop or strap 6 pivoted at 7 on the key lever. The rear end of the key lever is curved to creep along the under side of the fulcrum plate as the key is depressed, in order to produce a change in fulcrum, but the 35 key lever is prevented from moving endwise by a fixed transverse rod 8 arranged with a slot 9 in the key lever. 10 is the type bar, in this case pivoted at 11 in a hanger 12 attached by a screw 13 to the segment 14. The type end 40 15 of the type bar rests normally upon a pad 16. A coiled spring 17, attached at one end to the type bar and at its opposite end to the hanger or a washer 18 thereon, serves to return the type bar to normal position on the 45 pad after the type has left its impression on the paper on the platen 19. Pivoted at 20 in the heel of the type bar is a link 21 which at its rear end is pivoted at 22 to the upper end of a vertically arranged sub-lever or bell 50 crank 23. This bell crank is pivoted to the side of the key lever at 24, and the lower portion of the bell crank which projects down beyond the key lever is formed with a forwardly extending arm 25 to which is pivoted 55 at 26 an anti-friction roller 27. This roller

27 co-operates with two flat bearing surfaces 28 and 29, the one facing the other. Both of said bearing surfaces 28 and 29 are in substantially horizontal planes and parallel. In this case they are formed on the inner sides of 60 two plates or bars 30—31, which are preferably, though not necessarily, connected together by a vertical portion or web 32. The bars 30—31 and the connecting portion 32 form in cross-section a U-shaped fulcrum bar 65 with the mouth or open end extending horizontally towards the lower end of the bell crank, and so arranged as to receive the anti-friction roller 27 thereon.

In operation, when the key lever is depressed, the roller 27 will bear upon the surface 28 of the plate 30 and cause the bell crank to turn on its pivot 24 in the direction of the arrow, and so as to lift the type bar to printing position through the intermediate 75 connecting link 21. During the depression of the key lever to cause the type bar to print, the pivot 24 of course descends with the key lever and the roller 27 rolls forward on the bearing 28, the roller at this time 80 moving in a direction opposite to that of the upper end of the bell crank. When the key lever is released and restored by its spring 5, the roller 27 will bear against and roll on the opposite face 29 and cause the bell crank to 85 swing in a contrary direction. The distance between the bearing surfaces 28 and 29 is slightly greater than the diameter of the roll 27, so that the roll bears on only one surface at a time in the vibration of the bell 90 crank.

Referring now to Fig. 2, all of the parts shown are like those illustrated in Fig. 1, with the exception of the lower end of the bell crank and the fulcrum bar. In Fig. 2, 95 instead of having a single roll embraced by two opposite bearing surfaces, as in Fig. 1, it will be noted that there are two anti-friction rolls 27^a, 27^b and that these embrace the fulcrum bar 30^a; the upper roller 27^a operating upon a horizontal bearing surface 29^a and the lower roller 27^b operating upon a bearing surface 28^a. In this case the fulcrum bar is solid instead of U-shaped, as in Fig. 1, and the rolls 27^a and 27^b are pivoted 100 respectively upon two arms or extensions 25^a and 25^b of the bell crank, the latter being cut away sufficiently at 25^c to enable the parts to operate properly, and the lower bearing 28^a being curved or rounded to pre- 110

vent cramping action of the bell crank upon the fulcrum bar. When the key lever is depressed to swing the type bar upwardly, the roller 27^a bears upon the surface 29^a of the 5 fulcrum bar and causes the upper end of the bell crank to turn on its pivot 24 on the key lever in the direction of the arrow, the lower end of the bell crank at this time moving forward slightly and the rolls 27^a and 27^b riding 10 on their bearings 29^a and 28^a respectively. When the key lever is released, its returning spring causes the lever to ascend and the roll 27^b pressing and riding upon its bearing 28^a, causes the bell crank to be turned in the 15 opposite direction and the type bar to be brought back to its normal position upon the pad 16.

In both forms of my invention the bell crank is provided with an anti-friction roller 20 and the fulcrum bar with a bearing surface upon which the roller bears and travels during the vibration of the bell crank. The bearing surfaces are formed or arranged 25 transversely of the fulcrum bar and are elongated or extended so that the roller or rollers may bear and travel on these surfaces during the back and forth movements of the bell crank. In both instances there is a roller bearing action when the key lever is depressed 30 and when it is permitted to return to normal position; thus all sliding bearings between the bell crank and the fulcrum bar are avoided.

The fulcrum bar in each instance of my invention preferably extends entirely across 35 the system of bell cranks and is secured at its ends in the side frames of the machine.

What I claim as new and desire to secure by Letters Patent, is:—

40 1. In a typewriting machine, the combination of a type bar, a key lever, a fixed ful-

crum bar having transverse extended bearing surfaces for rolling means to bear and travel on, and a bell crank pivoted to the key lever and carrying rolling means for coöperating with said bearing surfaces. 45

2. In a typewriting machine, the combination of a type bar, a key lever, a fixed fulcrum bar having transverse extended bearing surfaces for rolling means to bear and travel 50 on, and a bell crank pivoted to the type bar and carrying one or more rollers to coöperate with said bearing surfaces.

3. In a typewriting machine, the combination of a type bar, a key lever, a bell crank 55 pivoted to the key lever, a roller pivoted on the bell crank, and a fixed fulcrum bar provided with transverse extended bearing surfaces between which said roller is received and with which it coöperates. 60

4. In a typewriting machine, the combination of a type bar, a key lever, a bell crank pivoted to the key lever, a roller pivoted on the bell crank, and a fixed fulcrum bar provided with transverse extended bearing surfaces at opposite sides of said roller and with 65 which said roller coöperates alternately during the operation of the parts.

5. In a typewriting machine, the combination of a type bar, a key lever, a bell crank pivoted to the key lever, a roller pivoted on the bell crank, and a fixed fulcrum bar U-shaped in cross-section, said roller entering 70 the opening in said fulcrum bar.

Signed at the borough of Manhattan, city 75 of New York, in the county of New York, and State of New York this 5th day of February, A. D. 1906.

HENRY A. SMEDBERG.

Witnesses:

JOHN N. OLIVER,
E. M. WELLS.

It is hereby certified that the State of incorporation of the assignee in Letters Patent No. 872,543, granted December 3, 1907, upon the application of Henry A. Smedberg, of New York, N. Y., for an improvement in "Type-Writing Machines," was erroneously given as "New York" whereas said State should have been given as *New Jersey*, as shown by the records of assignments in this office; and that the said Letters Patent should be read with this correction therein that the same may conform to the record of the case in the Patent Office.

Signed and sealed this 1st day of June, A. D., 1915.

[SEAL.]

J. T. NEWTON,

Acting Commissioner of Patents.
